COMBINED SIGNAL AND CONTROL MODULE

John Stallebrass, 15 Adam and Eve Mews,
London W. 8, England

Filed Dec. 22, 1967, Ser. No. 9,896

Claims priority, application Great Britain July 18, 1967

Term of patent 14 years

Int. Cl. D14—99; D26—01

U.S. Cl. D26—13

FIGURE 1 is a perspective view of said combined signal and control module as seen from one side and above said module having two identical sides;

FIGURE 2 is a bottom plan view; and

FIGURE 3 is an end elevation.

I claim:

The ornamental design for a combined signal and control module, substantially as shown and described.
